UNITED STATES PATENT OFFICE.

SOLOMON R. WASHER, OF ATCHISON, KANSAS.

DOOR FOR GRAIN-CARS.

SPECIFICATION forming part of Letters Patent No. 317,900, dated May 12, 1885.

Application filed January 22, 1885. (No model.)

To all whom it may concern:

Be it known that I, SOLOMON R. WASHER, a citizen of the United States of America, residing at Atchison, in the county of Atchison and State of Kansas, have invented certain new and useful Improvements in Doors for Grain-Cars; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to certain new and useful improvements in doors for grain-cars, the object of my invention being to provide a door which can be readily secured in position when desired, and removed when it is desired to unload the car, as will be hereinafter fully set forth, and pointed out in the claims.

In the accompanying drawings, which illustrate my invention, Figure 1 is a perspective view showing my improvement applied to a grain-car. Fig. 2 is a perspective view showing the door-frame and door detached, and Fig. 3 is a detailed sectional view.

A represents the door-frame, which consists of a sill-piece, B, which is centrally provided with a recess, b. To the door-sill are attached vertical uprights C C, which are of less width than the door-sill, these uprights having attached to their inner faces headed bolts c c. The door D is provided adjacent to each of its ends with vertical metallic plates d d, which are centrally provided with key-hole slots d', under which are formed recesses e, as shown in Fig. 3, said recesses being adapted to receive the heads of the bolts c. The door D is also re-enforced by a transverse batten, E. The central portion of the door near its base is provided with a vertical bolt, f, which is adapted to enter the recess b in the sill-piece B, and this bolt, in connection with the pivoted latch F, which is secured near one edge of the door to a block located above the batten E, will prevent a lateral movement of the door, as said latch will bear against the side of one of the uprights, while the bolt enters the recess in the sill-piece. Adjacent to the block to which the latch is pivoted is secured

a ratchet-bar, G, the object of said ratchet-bar being to form a fulcrum or resting-point for a lever which is employed to bring the latch to a horizontal position.

When it is desired to place the door in position, the larger portion of the key-hole slots in the vertical plates d are placed over the headed bolts c, the latch F is then forced downwardly, as described, which causes a lateral movement of the door, and causes the head of the bolt to engage with the smaller portion of the slots, thus preventing the door falling inwardly. It will be seen that the weight of the material in the car will force said door against the inner side of the vertical upright, and the retaining means will be subject to but little strain; also, that when the door is in position the slots will be entirely covered, so that the grain cannot find access to the recesses under said slots. If desirable, the latch F may be centrally pivoted to the door, so that each of its ends will abut against the upright frames, and said frames may be provided with vertical and inclined recesses for the reception of said ends. Bails may also be attached to the door, so as to extend over the latch. The bolt f is a precautionary feature designed to hold the door in position against tendency to shift should the latch F accidentally become disengaged. When the latch F is to be operated to shift the door, the latch is forced down by a bar or lever having a bearing or fulcrum against the underside of one of the teeth of the ratchet-bar, while the end of the lever rests upon the latch and thus forces it down.

I am aware of Patent No. 211,776, granted January 28, 1879, to J. R. Pelton and F. Hall, and No. 174,239, granted February 29, 1876, to Z. M. Hibbard; and I do not wish to be understood as claiming, broadly, any features disclosed in said patents.

I claim—

1. In a grain-car door, the frame having vertical uprights, with projecting headed pins attached to the inner sides thereof, in combination with the door D, provided with vertical metallic plates with key-hole slots formed therein, and a pivoted latch adapted to abut against one of the vertical uprights of the door-frame, substantially as shown, and for the purpose set forth.

2. In a door for grain-cars, the frame A, consisting of sill-piece, vertical uprights having headed bolts attached to the inner side of said uprights, in combination with the vertical metallic plates *d*, with key-hole slots and recesses, transverse batten E, pivoted latch F, ratchet-bar G, adjacent thereto, and bolt *f*, the parts being organized substantially as shown, and for the purpose set forth.

In testimony whereof I affix my signature in presence of two witnesses.

SOLOMON R. WASHER.
